(57) CLAIM

The ornamental design for a wall base with angled top and groove, as shown and described.

DESCRIPTION

FIG. 1 is a perspective view of a wall base with angled top and groove embodying this invention;

FIG. 2 is a top view of the wall base with angled top and groove as shown in FIG. 1;

FIG. 3 is a front view of the wall base with angled top and groove as shown in FIG. 1;

FIG. 4 is a right side view of the wall base with angled top and groove as shown in FIG. 1;

FIG. 5 is a rear view of the wall base with angled top and groove as shown in FIG. 1;

FIG. 6 is a left side view of the wall base with angled top and groove as shown in FIG. 1; and,

FIG. 7 is a bottom view of the wall base with angled top and groove as shown in FIG. 1.

The claimed design is broken in the center to indicate indeterminate length.
